BUNCH BUILDER MECHANISM

Ransom R. Gibson, Wattsville, S. C.

Application April 17, 1947, Serial No. 742,186

5 Claims. (Cl. 242—43.3)

1

The present invention relates to a bunch building mechanism for filling quills or bobbins of spinning frames.

An important object of the invention is to provide a latch which automatically moves over the ring rail, when the ring rail is moved downwardly to doff the spinning frame, and to limit the upward movement of the ring rail during the formation of the bunch, the latch being automatically shifted to release the ring rail for upward movement after the formation of the bunch so that the complete traverse may be made to fill the quill or bobbin.

A further object of the invention is to provide a latch of the above mentioned character which may be manually operated to release the ring rail for upward movement, at any time, without disturbing the arrangement of associated elements, thus enabling the doffer to raise the ring rail and again lower the same for taking the slack out of the filling.

A further object of the invention is to provide a device of the above mentioned character which is positive and reliable in operation.

In the accompanying drawings forming a part of this application and in which like numerals are employed to designate like parts throughout the same,

Figure 1 is a side elevation of bunch building mechanism embodying my invention, showing the latch arranged over the ring rail.

Figure 2 is a similar view showing the latch moved to release the ring rail.

Figure 3 is a plan view of the mechanism, showing the latch over the ring rail, and,

Figure 4 is a side elevation of the latch mechanism removed.

The spinning frame comprises ring rails 10, and base rails 11, upon opposite sides of the spinning frame and a supporting frame 12. The ring rails 10 are raised and lowered in unison. This is the conventional spinning frame.

Arranged inwardly of the ring rails 10, and near one ring rail 10, is a vertical shaft 13, journaled in a bearing 14, fixed to the frame 12. The numeral 15 designates a vertical U-shaped latch, having knuckles 16 pivotally mounted upon the vertical shaft 13 so that the latch 15 swings horizontally. This U-shaped latch includes horizontal ends 17 and a vertical side 18. Surrounding the shaft 13 is a torsional coil spring 19, one end of which is attached to the lower arm 17 and the opposite end of which is attached to a collar 20, clamped to the shaft 13. This spring 19 is tensioned to swing the lower end or arm 17 into

2

engagement with a depending pin 21, rigidly secured to a collar 22, rigidly clamped to the shaft. The collar 22 and spring 19 hold the latch 15 against longitudinal movement upon the shaft 13. The spring 19 is tensioned to swing the end or lower arm 17 into engagement with the pin 21, as stated, but the latch may be swung upon the shaft 13 in a direction from the pin 21, to bring the latch 15 out of the path of travel of the ring rail. When the shaft 13 is turned in the direction of the arrow, the pin 21 will engage the lower end or arm 17 and swing the latch 15 in one direction, out of the path of travel of the ring rail.

After the spinning frame is doffed and at the starting of the bunch building period, the U-shaped latch 15 is positioned over the ring rail 10 in its path of travel and will prevent the ring rail from moving up too high while forming the bunch, but permitting of the short traverse of the ring rail. At the beginning of the formation of the bunch, the doffer may want to remove the slack from the filling. To accomplish this, the latch 15 is manually swung from over the ring rail 10, and will occupy a position at the side of the ring rail. The latch 15 will then move from the pin 21, in opposition to the spring 19. The ring rail may be raised and lowered which will remove the slack from the filling. When the ring rail is raised to the uppermost position it is still beneath the top of the latch 15 and holds the latch from the pin. When the ring rail is returned to the lowered position or doffed position the latch will automatically swing over the ring rail and again hold the same lowered during the bunch building period.

The vertical shaft 13 has a horizontal beveled gear 22', rigidly secured thereto, engaged by a beveled gear 23, rigidly mounted upon a horizontal shaft 24, journaled in a fixed bearing 25. The shaft 24 has a crank 26, rigidly secured thereto. This crank is provided with a pivot element or bolt 27, operating within an elongated slot 28, formed in a coupling 29. This coupling has a screw threaded opening 30, for receiving the screw threaded end of a connecting rod 31, having a curved portion 32.

The numeral 33 represents a vertically swinging builder arm, suitably connected with the ring rail to raise and lower it. Pivotally mounted upon the builder arm 33 is a curved toothed arm 34. The builder arm carries a roller 35, to be engaged by the main cam 36, and a bunch cam 37 engages the toothed arm 34. Both cams are mounted upon a rotary shaft 38. The builder

arm 33, toothed arm 34, roller 35, cams 36 and 37, and shaft 38 are substantially identical with those shown in the patent to J. L. Lyle, 2,140,084 and they are also shown in my copending application for Bunch builder, filed September 13, 1946, Serial No. 696,865. The bunch cam 37 not only raises and lowers the toothed arm 34 but swings the toothed arm upon its pivot, from the position shown in Figure 1, to the position shown in Figure 2. The curved end 32 of the connecting rod is pivotally connected with one end of the toothed arm 34, shown at 39.

Figure 1 shows the relative position of the parts at the beginning of the bunch forming period. The latch 15 is now engaging over the ring rail 10. The bunch cam 37 is rotating in the direction of the arrow, and the toothed arm 34 is raised and lowered, and imparts a short stroke to the builder arm 33, which is transmitted to the ring rail 10. While the toothed arm 34 is being reciprocated vertically it is swinging to the left and downwardly. During this swinging movement of the toothed arm 34, the pivot 27 is at first spaced from the upper end of the slot 28, but continued movement of the toothed arm 34 and rod 31 brings the upper end of the slot 28 into engagement with the pin 21, and when the rod 31 has reached the end of its downward travel, Figure 2, the lever 26 has been swung downwardly to the lowered position. This movement of the lever 26 turns the shaft 24 counter-clockwise, Figure 1, turning gear 23 counter-clockwise, Figure 1, which turns gear 22 clockwise, Figure 1. The shaft 13 is turned clockwise and the pin 21 engages the lower end of arm 17 and swings the latch 15 from over the ring rail. The ring rail now rises and assumes the position shown in Figure 2. The main cam 36 now operates the builder arm for effecting the complete traverse of the ring rail. When the spinning frame is doffed, the ring rail 10 is lowered, Figure 1, and the latch 15 will engage over the ring rail, when the shaft 13 is turned counter-clockwise, Figure 1. This is effected when the toothed arm 34 is swung under the bunch cam 37, when the spinning frame is doffed, as is well known. When the shaft 13 turns counter-clockwise, Figure 1, spring 19 causes the latch 15 to remain in engagement with the pin 21 and follow the same.

It is thus apparent that I have provided a latch to limit the upper movement of the ring rail during the bunch building period, and which is automatically moved out of the path of travel of the ring rail after the bunch is formed and during the filling period. The latch automatically moves over the ring rail when the spinning frame is doffed. Since the latch 15 is pivotally mounted upon the vertical shaft 13 it may be swung manually in one direction out of the path of travel of the ring rail 10, independently of the gearing. This will enable the doffer to raise and lower the ring rail to take up the slack in the yarn or filling being wound upon the quill, without turning the shaft 13. When the ring rail 10 is in the uppermost position it is beneath the top of the latch 15.

It is to be understood that the form of my in-

vention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. In a bunch builder mechanism, a vertically movable ring rail, a substantially vertical shaft arranged near the ring rail, a horizontally swinging latch pivotally mounted upon the shaft for movement over the ring rail, means mounted upon the shaft and contacting with the latch to swing the latch in one direction when the shaft is turned, the latch being movable from the means, and means to turn the shaft upon its longitudinal axis.
2. In a bunch builder mechanism, a vertically movable ring rail, a substantially vertical shaft arranged near the ring rail, a latch pivotally mounted upon the shaft to turn substantially horizontally and to be moved over the ring rail, a member mounted upon the shaft to turn therewith and contacting with the latch to swing it in one direction, the latch being manually removable from the member, a spring to turn the latch toward the member, and means to turn the shaft.
3. In a bunch builder mechanism, a vertically movable ring rail, a substantially vertical shaft mounted near the ring rail, a generally U-shaped latch including a side and ends, said ends having knuckles to pivotally receive the shaft, a pin mounted upon the shaft to turn therewith and engaging the side of one end, such end being movable from the pin, a spring to swing the latch upon the shaft so that said end is brought into engagement with the pin, gearing to turn the shaft, and means to operate the gearing.
4. In a bunch builder mechanism, a vertically movable ring rail, a substantially vertical shaft mounted near the ring rail, a latch mounted upon the shaft for coaction with the ring rail, a substantially horizontal shaft mounted near the substantially vertical shaft, gearing connecting the shafts, a lever mounted upon the substantially horizontal shaft, means to move the lever including a pivoted toothed arm, and a connecting rod attached to the toothed arm and connected with the lever.
5. In a bunch builder mechanism, a vertically movable ring rail, a substantially vertical shaft mounted near the ring rail, a horizontally swinging latch carried by the shaft for coaction with the ring rail, a beveled gear mounted upon the shaft, a substantially horizontal shaft mounted near the substantially vertical shaft, a beveled gear mounted upon the substantially horizontal shaft and engaging the first named beveled gear, a lever mounted upon the substantially horizontal shaft and carrying a pin, a connecting rod provided with a member having an elongated slot to receive the pin, and means to move the connecting rod including a pivoted tooth arm having pivotal connection with the rod.

RANSOM R. GIBSON.
